UNITED STATES PATENT OFFICE.

HUGO BORCHARDT, OF CHARLOTTENBURG, GERMANY.

HOLDER FOR INSERTIBLE MAGAZINES.

989,560.

Specification of Letters Patent. Patented Apr. 18, 1911.

Application filed November 3, 1910. Serial No. 590,515.

To all whom it may concern:

Be it known that I, HUGO BORCHARDT, a citizen of the United States of America, residing at No. 31 Kantstrasse, Charlottenburg, 5 Germany, have invented new and useful Improvements in Holders for Insertible Magazines, of which the following is a specification.

This invention relates to an improved 10 holder for insertible magazines, which is so arranged that it grips the insertible magazine at its sides whereby a loosening of the holder under the influence of the recoil is completely prevented. For this purpose, the 15 holder is in the form of a spring U-shaped yoke, which engages in the sides of the insertible magazine by means of projections provided on the legs of the yoke and extending through the stationary magazine casing.

20 A constructional form of the invention is shown in the accompanying drawing by way of example.

Figure 1 is a longitudinal elevation—partly in section—of the middle part of the 25 fire arm; Fig. 2 shows the magazine casing with the insertible magazine and the holder in horizontal cross-sections; Fig. 3 is the same section as Fig. 2, the holder, however, being out of engagement with the insertible 30 magazine.

As already stated, the holder *h* is in the 35 form of a U-shaped yoke, whose spring legs engage or embrace that part of the magazine casing *g* which projects below the stock, the part in front of the magazine casing being free and serving as a grip or pressure piece for operating the holder. The free ends of the legs of the yoke are provided with projections *h'* which extend through holes of 40 the stationary magazine casing *g* and engage in corresponding lateral depressions or recesses *m'* of the insertible magazine.

The operation of the holder, which is under the influence of a spring *f* is effected by 45 a simple displacement in the longitudinal direction (rearwardly) by which displacement as shown in Fig. 3 the projections *h'* which are beveled on their rear faces are brought out of engagement with the corresponding recesses so that the insertible magazine can be withdrawn downward. The projections 50 are offset rectangularly at their front faces

in order that the engagement may also be maintained against the recoil.

What I claim as my invention and desire 55 to secure by Letters Patent is:—

1. In a fire-arm, the combination with a magazine casing, of means for engaging an insertible cartridge magazine or clip, said means comprising a spring yoke having arms 60 engaging the sides of the cartridge clip.

2. In a fire-arm, the combination with a magazine casing, of means for engaging an insertible cartridge magazine or clip, said means comprising a spring yoke having arms 65 embracing the magazine casing and projecting through the sides of the magazine casing to engage the sides of the cartridge clip.

3. In a fire-arm, the combination with a magazine casing, of means for engaging an 70 insertible cartridge magazine or clip, said means comprising a spring yoke having arms embracing the magazine casing, movable longitudinally with relation to the magazine casing, and having projections projecting 75 through the sides of the magazine casing to engage the sides of the cartridge clip, and means for disengaging the arms of said spring yoke from the cartridge clip when the yoke is moved longitudinally. 80

4. In a fire-arm, the combination with a magazine casing, of means for engaging an insertible cartridge magazine or clip, said means comprising a spring yoke having arms 85 embracing the magazine casing, movable longitudinally with relation to the magazine casing and having beveled projections projecting through the magazine casing to engage the sides of the cartridge cup and adapted, when moved longitudinally, to be 90 disengaged from the cartridge clip by the engagement of said beveled projections with a part of the magazine casing. 95

5. In a fire-arm, the combination with a magazine casing, of means for engaging an 95 insertible cartridge magazine or clip, said means comprising spring arms upon either side of the magazine casing, movable longitudinally thereof, and having projections projecting through the sides of the magazine 100 casing to engage the sides of the cartridge clip and means for disengaging the spring arms from the cartridge clip when they are moved longitudinally.

6. In a fire arm the combination of a magazine casing, and a catch device for holding an insertible magazine therein, said device being adapted to engage and disengage
5 said magazine by inward and outward movements, and means for so moving said device when the latter is moved in a plane at right angles to its inward and outward movements.

In witness whereof, I have hereunto signed my name in the presence of two subscribing 10 witnesses.

HUGO BORCHARDT.
